(57) **CLAIM**

The ornamental design for a chandelier, as shown and
described.

DESCRIPTION

FIG. 1 is a front view of a chandelier with lighting elements
thereof shown in phantom, the rear view being a mirror
image thereof;

FIG. 2 is a top view thereof; and

FIG. 3 is a front view thereof.

The broken line showing of the lighting elements is for
illustrative purposes only and forms no part of the claimed
design.
